UNITED STATES PATENT OFFICE.

WALTER E. HOSCH, OF ST. LOUIS, MISSOURI, ASSIGNOR TO HOSCH MECHANISMS CORPORATION, OF ST. LOUIS, MISSOURI, A CORPORATION.

MACHINE FOR INTEGRATING SHEET MATERIAL.

1,404,026.

Specification of Letters Patent. Patented Jan. 17, 1922.

Application filed October 11, 1917. Serial No. 196,097.

To all whom it may concern:

Be it known that I, WALTER E. HOSCH, a citizen of the United States, residing in St. Louis and State of Missouri, have invented 5 new and useful Improvements in Machines for Integrating Sheet Material, of which the following is a specification.

This invention relates to a machine for integrating the areas of articles irregular 10 in outline and which may lack uniform continuity of body, and is particularly adapted for use in measuring leather, in the form of tanned hides.

It is the purpose of the invention to provide a machine of this character which shall 15 be simple in construction, positive, direct and reliable in action and which shall so closely approximate absolute accuracy in the measuring operation that the element of 20 error is, for all practical purposes, nil.

Various types of machines for measuring leather have been heretofore suggested, and 25 at least one of these types is now in more or less general use. This machine may be described as comprising a greater or less number 30 of series of traction, or measuring wheels, revolving in contact with a roller, and which are raised according to the varying width of the article passed through, each traction wheel measuring lineally the length 35 of surface that passes over it, and being so raised by its movement actuates a device for winding up a cord, or the like, whereby its peripheral movement is supposed to 40 be accurately transmitted. The amount of cord wound up by the different wheels, or the amount of each wheel's peripheral movement, is transmitted to a system of levers, which in turn transmit their aggregate motion to an indicating dial. While machines 45 of the type referred to are, as stated, in commercial use at the present time, it is known that they are not reliable in operation, nor accurate in results, and that they 50 require adjustment from time to time to correct, as far as possible, the inaccuracy of operation. For this latter purpose a card, or a chart of known area is usually furnished with each machine so that by passing 55 it through the machine, variations from the correct measurement may be detected and adjustment of the measuring units may be made to correct the fault. Under any circumstances, however, measurements indicated by this machine will at best be only

approximately accurate, the margin of error being very considerable. This is due, among other things, to the fact that the measuring wheels are relatively large in diameter, usually about six inches, and the 60 upper forward edge of the leather engages the periphery of the wheels and causes a considerable turning movement thereof before the wheels actually pass onto the upper surface of the leather, and this turning movement is registered on the measuring dial, 65 although as a matter of fact, no leather has been actually measured. The same false measurement occurs as the rear edge of the leather passes from under the wheels. 70 Another source of inaccuracy is attributable to the relation of the aggregating units of the machine to each other, which relation is one of proportion, depending wholly on the principle of leverage, and not one of direct, 75 positive, and invariable mechanical co-ordination. Such a construction presents opportunity for lost motion in operation, and variations in movement of the measuring units, such, for example, as would be caused 80 by contraction or expansion of the levers, or stretching of the cords operating the levers. There can, therefore, be no fixed and accurate relation between the movement of the measuring wheels and the movements 85 of the aggregating levers. Moreover, such relation is not a scientifically calculated one, so that the movement of the registering mechanism, or of the hand of the indicating dial in relation to each measuring wheel, can 90 be forecast with absolute precision, as may be done, e. g., in the case of the hands of a clock, but is purely empirical, and the value of such movement can only be determined by a process of calibration. 95

Finally, another source of inaccuracy in the machine referred to lies in the fact that the measuring wheels are about an inch in width and are separated a distance of about two inches, from center to center, it being 100 impracticable to locate the wheels closer together owing to the large number of levers which would have to be employed. Such a distance between the measuring wheels renders it impossible to insure that variations 105 in the continuity of the leather produced by holes, irregularities of outlines, etc., to the extent of the area involved, shall be accounted for by way of deduction, in the measurement of the leather indicated. This 110

is, perhaps, the most serious disadvantage of the machine referred to, as it is obvious that with relatively widely separated measuring wheels of the width indicated, the area of 5 the intervening space between two measuring wheels in engagement with the surface of the leather will be represented in the actual measurement of the hide, whether such space be occupied by the material of the 10 hide, or be an open place therein. And further, it is also obvious that with wheels of such width it will frequently occur that the extreme edge only of one or the other of said wheels will be traveling on the surface 15 of the hide and that the total area embraced in the travel of the hide under such wheel and an adjacent wheel, i. e., the distance the hide travels multiplied by the distance between centers of the wheels, will 20 be added to the area of the hide, although only a fraction of the area thus measured will be represented by the material of the hide.

The latter source of error in machines for 25 measuring leather cannot in the nature of things be entirely eliminated, but it is a leading characteristic of my machine that such source of error is reduced to the minimum, and, in fact, rendered practically 30 negligible, by the use of a large number of relatively narrow measuring wheels, located in close juxtaposition, say, one-half inch from center to center, so that only extremely small areas of discontinuity of material 35 will escape deduction from the gross area of the hide. I further overcome the objection noted incident to the use of measuring wheels of large diameter by the employment of relatively small measuring 40 wheels, such wheels having a diameter of about one and one-half inches. Aside from the feature of inaccuracy in operation, a pronounced disadvantage of this prior machine is the fact that all of the aggregating units 45 must be returned to normal, or zero, position after each measuring operation, adding enormously to the wear of the machine and limiting materially the speed of operation. Furthermore, the extent of any single 50 measurement is limited by the size of the pulleys on which the cords are wound, these pulleys, at the most, being capable of only one complete revolution. As distinguished from such operation, a machine of the type 55 of my invention mechanically aggregates the movements of the measuring wheels by a system of gearing, and the measuring operation may be continued indefinitely, the only resetting required being that of the 60 dial for indicating the measurements of individual hides, if such dial be used, which operation is effected automatically by merely pressing a button.

With the foregoing in mind, it is one of 65 the objects of my invention to provide a ma-

chine of the character indicated in which a large number of relatively narrow measuring wheels, arranged in close juxtaposition to each other may be employed, as compared with a comparatively small number of relatively wide wheels, separated from each other by a considerable space, as is now the case, and to so co-ordinate these measuring wheels with registering mechanism, that the movement of one, or the aggregate movement of several or all of said measuring wheels will be transmitted directly and with uniform accuracy to the registering mechanism and in exact calculated proportion to the extent of movement of the respective 80 wheels.

With such objects in view my invention comprises a series of feed and measuring wheels, the latter being co-ordinated with a diminishing series of differential-gear 85 units in such manner that adjacent pairs of measuring wheels control, respectively, the actuating, or outer members of a line, or series, of such differential-gear units, while the inner, or intermediate members of each 90 pair of these units transmit their motion to the actuating members of another series of differential-gear units, the intermediate members of each pair of which latter transmit their movement in turn to the actuating 95 members of a third series of differential-gear units, and so on, until finally the movement of the intermediate member of a final differential-gear unit is transmitted to the registering mechanism. In the particular 100 embodiment of my invention shown in the drawings, there are thirty-two measuring wheels, and there are, accordingly, sixteen differential-gear units in the first series, each succeeding series of differential-gear units 105 diminishing in number by one-half, up to a single, and final unit. Owing to the flexible character of the differential-gear, that is to say, the possibility of actuating the intermediate member of the unit by rotating 110 either or both of the outer members, the motions of the measuring wheels are simultaneously aggregated and transmitted immediately to the registering mechanism by direct gear connection; thus the registering 115 mechanism is not only positively driven directly from the measuring wheels but the extent of movement of the measuring wheels is accurately transmitted to the registering mechanism by means of the interposed gearing. 120

There are various important features of construction which contribute to the general operation of the machine but these will be better understood as they are reached in 125 order, in connection with the detailed description of the machine to be given.

I may state that I have used the term "registering mechanism" above, and may subsequently use the same, as embracing a 130

device for registering the total area of a number of hides passed through the machine and an indicating dial for indicating the area of each hide as it is passed through the 5 machine. As either of these devices may be used without the other such designation will, unless otherwise indicated, refer to either or both of such devices.

The accompanying drawings illustrate a 10 commercial embodiment of my invention. The machine from which these drawings were made, however, is the first machine constructed embodying my invention, and I contemplate various changes, coming within 15 the scope of my invention as outlined in the following specification and claims, as will be later indicated. Such changes, however, relate more especially to matters of degree and arrangement and not to the principle of 20 operation involved.

In said drawings:

Figure 1 is a view in front elevation of a measuring machine constructed according to my invention;

25 Figure 2 is a view in end elevation thereof;

Figure 3 is a view in front elevation on an enlarged scale of the machine minus the supporting standards, and with the front part of the casing and the dial removed;

30 Figure 4 is a view in front elevation, on a further enlarged scale, of the central portion of the machine shown in Figure 3, intended more particularly to illustrate the mechanism entering into the operation of the 35 indicating dial;

Figure 5 is a sectional view taken on the line 5—5 of Figure 4 and on a further enlarged scale;

40 Figure 6 is a sectional view taken on the line 6—6 of Figure 4, and on the same scale as Figure 5;

45 Figure 7 is a sectional view taken on the line 7—7 of Figure 4, and on the same scale as the latter figure, and partly sub-sectioned;

50 Figure 8 is a fragmentary view in front elevation on an enlarged scale, showing the central portion, or group, of the feed and measuring wheels and connected mechanism shown at the lower part of Figure 3, one of the feed wheels being shown in section;

Figure 9 is a sectional view taken on the line 9—9 of Figure 8;

55 Figure 10 is a sectional view taken on the line 10—10 of Figure 9;

Figure 11 is an edge view on an enlarged scale of one of the differential-gear units;

Figure 12, is a sectional view taken on the line 12—12 of Figure 11;

60 Figure 13, is a sectional view taken on the line 13—13 of Figure 12.

Referring now to the drawings, the numeral 1 indicates, generally, a standard supporting the machine. Mounted on this 65 standard is the main frame of the machine

which comprises four transverse angle bars, two of said angle-bars, indicated by the numerals 2, 3, respectively, (Fig. 9) being located at the front of the machine, and two, indicated, respectively, by the numerals 4, 5 at the rear of the machine. Secured at

opposite ends of the angle-bars are two end plates, 6, 7, respectively, (Fig. 3). Secured

to the rear-angle bar 4 is a back plate 8, on which the main portion of the mechanism is 70

mounted. The numeral 9 (Figs. 2 and 4) indicates a casing member secured to the upper edge of the back plate 8, and projecting

beyond the front side of said back plate, and the numeral 10 (Figs. 1 and 9) indicates a 80

removable casing member, having an upper vertical portion 11 which is fitted to the cas- 85

ing member 9, and a lower curved portion 12 which is supported upon cleats 13 on the end walls 6, 7, and secured by set-screws 14 to 85

posts 15 mounted on the back plate 8. The 90

casing members 9 and 10 inclose and protect the operating mechanism. Extending trans- 95

versely across the machine and mounted in its opposite ends in the end plates 6 and 7 90

is a shaft 16 on which is keyed a feed roller 17 (Figs. 1, 3, 8 and 9). The shaft 16 ex- 95

tends through end plate 7, as indicated by 19 in Figures 1 and 3, and such projecting

end may be adapted to receive a crank han- 95

dle 20 for turning. Preferably, the roller 17 is motor driven, to which end I mount a 100

small motor 21, (Fig. 2) on the rear side of the back plate 8 at the right of the machine, which communicates its motion to a pulley 100

22. Mounted on the end plate 8 is a pulley 23 which is connected to the pulley 22 by a 105

belt 24. The pulley 23 communicates its motion to a small pulley 25 which in turn, 110

through the medium of a belt 26, imparts its motion to a pulley 27, also mounted on the 115

end plate 7. The hub of the pulley 27 is provided with a spur gear 28 which is in mesh with a large gear 29 fixedly secured on the projecting end of the shaft 16. 110

Mounted at intervals on the upper mem- 115

ber of the angle bar 4 (Figs. 9 and 10) is a series of brackets 30, and supported in these

brackets and mounted at its opposite ends in the end plates 6 and 7 is a rod 31. Pivot- 120

ally mounted at their inner ends on the rod 31 are a series of arms 32 each of which at 125

its outer end is provided with a cylindrical bearing 33 (Fig. 8) on which is rotatably mounted the hub 34 of a feed wheel 35. 120

These feed wheels rest by gravity upon the upper surface of the roller 17. Pivotally 125

mounted at their inner ends on the rod 31 is also a series of pairs of arms 36. Between

the outer ends of each pair of these arms is 125

mounted on an axle 37 a measuring wheel 38. As shown particularly by Fig. 3, thirty-two

of these measuring wheels are employed, in the embodiment of the invention shown in the drawing. These wheels extend in line 130

from side to side of the machine. In the commercial machine, however, I contemplate using a greater number of measuring wheels and to locate them much closer together than 5 represented to be the case in the drawings. In the present case the measuring wheels are supposed to be separated a distance from each other of one inch from center to center and they are four and one-half inches in circumference. 10 Registering mechanism is provided, and means for connecting the same with the measuring wheels. This means is constructed so that it is capable of continuous indefinite rotation in one direction in the 15 operation of the machine, thereby rendering it unnecessary to reverse the movement of any parts, when using the machine. Mounted on the side of one of the arms 36 of each pair of said arms is a screw-threaded stud 20 39 which receives a set screw 40 the lower end of which engages the bottom member of the angle bar 4. The set-screws 40 operate to hold the arms 36 in such position that the measuring wheels 38 will at all times be out 25 of contact with the surface of the feed rollers 17. By adjusting the set screws 40, the distance the measuring wheels are separated from the feed roller 17 may be varied as circumstances may require. Fixedly secured 30 on the side of each measuring wheel 38 is a driving gear 41 which is in mesh with an idle gear 42 rotatably mounted by means of an axle 43 in and between the pair of arms 36. Each of the idle gears 42 in turn meshes 35 with a second idle gear 44 which is rotatably mounted on the rod 31. Each pair of arms 36 is yieldingly held with the screw 40 in contact with the angle bar 4 by means of a coil spring 45, the lower end of which is engaged in a plate 46 mounted on the angle bar 4 and the upper end of which engages over a stud 47 extending between each pair of plates 36. Pivottally mounted on each stud 47 is a ratchet 48 which engages the teeth of the 40 idle gear 42, allowing it to turn in one direction, caused by the engagement of material being measured with the measuring wheels 38, but preventing its movement in the opposite direction. As the driving gear 41 on 45 each measuring wheel is in mesh with an idle gear 42, and as each idle gear is in a train of gears leading to the registering mechanism, as will later be described, backward movement not only of the measuring 50 wheels 38 but of all the measuring units is prevented by the ratchets 48. A stud 49 mounted on the side of each arm 32 prevents the ratchet 48 from being accidentally turned or thrown backward out of position. 55 A plate 50, extending the entire width of the machine between the end plates 6 and 7, is secured to the upper side of the angle bar 2 and projects inward into close proximity with the upper surface of the feed roller 17, 60 and serves as a support and guide for the 65

hides, pieces of leather, or other material to be measured, and which must be passed between the rotating roller 17 and the feed wheels 35. Preferably, also, a table 51, suitably supported by bracket arms 52 (Fig. 2), projects forwardly of the machine as a continuation of the plate 50 and serves as a support for the material to be measured. I will now describe the mechanism by which the movement of the measuring wheels 38 caused by the passage of the material between them and the feed roller 17 is transmitted to the registering mechanism to indicate the area of such material.

I have heretofore referred to each idle gear 44 as being rotated by an idle gear 42 from the driving gear 41 on a measuring wheel 38. Two idle gears 44 are connected in this manner with the gear 41 of each pair of measuring rollers 38, and the two members of each set of idle gears 44 are in mesh, respectively, with two outer members 53, 54 of a differential-gear unit. (Figs. 3, 8, 11, 12 and 13). All of these differential units are, except as to the length of the connecting shafts and in one instance as to the size of the unit, the same in construction and operation, and a description of one will suffice for all. This description will be given in connection particularly with Figs. 11, 12 and 13, and it will be assumed that the differential-gear unit illustrated in these figures is one of the first line of such units above referred to. Each of these differential-gear units is supported independently in a pair of brackets 55, 56, respectively, and comprises the two gears 53, 54, above referred to, constituting the outer members of the unit, and a gear 57 and circular plate 58, connected together by ports 59, constituting the inner or intermediate member of the gearing. The gear 53 is fast on a shaft 60, which is rotatably mounted at its outer end in a bearing 60^a on the bracket 56 and passes loosely through the hub 61 of the gear 57. At its inner end the shaft 60 has fixedly secured thereon a relatively large gear 62. The gear 54 is fixedly secured on a short shaft 63 the outer end of which is rotatably mounted in a bearing 64 on the bracket 55. The shaft 63 passes loosely through the plate 58 and has fixedly secured on its inner end a gear 65 of the same size as the gear 62. The numerals 66 and 67 indicate, respectively, two small gears which are in mesh with each other, and the axles of which are rotatably mounted at their opposite ends in the gear 57 and plate 58 near the periphery thereof. The gear 66 is in mesh with the gear 65 and the gear 67 is in mesh with the gear 62. Owing to this arrangement it will be clear that the intermediate member of the differential unit, comprising the gear 57 and plate 58, may be rotated from either shaft 60 or 63 independently, by turning, respectively, gear 125

wheels 53 or 54, or that it may be rotated by turning both of said shafts simultaneously. There are sixteen of the differential-gear units in the first line or series, comprising 5 those which are in direct gear relation with the series of gears 54. As shown more clearly by figures 3 and 8, the intermediate gears 57 of successive pairs of differential-gear units of the first line or series, are in mesh 10 with the outer members, or gears 68, of the second line, or series, of differential-gear units, in which series there are eight of such units; the intermediate members, or gears, 69, of successive pairs of this second 15 series of differential-gear units are in mesh with the outer members, or gears, 70 of a third series of differential-gear units, four of such units being comprised in this series; the intermediate members, or gears, 71 of 20 each pair of this third series of differential-gear units is in mesh with the outer members, or gears, 72 of a fourth series of differential-gear units, which series comprises two of such units, and finally the intermediate members, or gears, 73 of this 25 last series of differential-gear units are in mesh with the outer members or gears 74 of a final differential-gear unit, the intermediate member of which latter is indicated 30 by 75. Thus it will be seen that the intermediate member of each individual differential-gear unit will be caused to aggregate the movements of the two outer members; that the aggregate movement of all of the 35 intermediate members of the first series of differential-gear units is transmitted to the outer members of the second series of such units which in turn, and in like manner transmit their aggregate movement to a 40 third series, and so on, until a pair of units transmit their aggregate movement to a final differential-gear unit, the aggregate movement of the intermediate member 75 of which will be the aggregate movement of 45 all of the measuring wheels 38 actuated, and this movement is adapted to be transmitted to the registering mechanism. To this end a relatively large gear wheel 76 is made fast with the hub 77 of the intermediate member 75 of the last differential-gear unit and this gear wheel is in mesh 50 with a small gear 78 rotatably supported on a bracket 79. The gear 78 is in mesh with a gear 80 which is formed integral 55 with a sliding clutch member 81 (Fig. 7). This clutch member is loosely and slidably mounted upon a hollow shaft 82, which is rotatably mounted in a bearing 83, of a bracket 84. Extending through the shaft 60 82 is a rod 85, provided intermediate its length with a transverse pin 86, which extends through slots 87, in opposite sides of the hollow shaft 82 and engages the side of the clutch member 81. Beyond the clutch 65 member 81 the end of the shaft 82 is rotatably mounted in a bracket-arm 88, and between this bracket arm 88 and the clutch member 81 is fixedly secured on the shaft 82, a clutch member 89 which is formed as a unitary part of a bevel gear 90. A coil 70 spring 91 is interposed between the bracket 84 and the clutch-member 81, and tends normally to keep the clutch-members 81 and 89 in engagement. The bevel gear 90 is in mesh with a bevel gear 92 which is fast 75 on a hollow shaft 93 which is rotatably mounted on a stub shaft 94 projecting from the end of the bracket arm 88 (Fig. 5). Fixedly secured on the hollow shaft 93 adjacent to the bevel gear 92 is a cam 80 plate 95, and adjacent to the said cam plate and fast with it is a pinion 96. Mounted on the back plate 8 near the top thereof is a bracket member 97 in which is screwed the end of a bearing 98 and on this bearing 85 is rotatably mounted a large gear wheel 99 which is in mesh with the pinion 96. A smaller gear 100 is formed as a unitary part of the gear 99, but in spaced relation thereto. Rotatably mounted on the hollow 90 shaft 93 is a large gear 101 which is in mesh with the gear 100. The gear 101 has a shouldered hub 102 against the shoulder of which rests a disk 103 which supports the central portion of a circular plate 104 95 which is secured by means of screws to posts 105. Secured on the outer face of the plate 104, is a paper, or other dial 106, (see also Fig. 1), which is provided with suitable numbers as shown, to indicate the measurement in square feet and tenths of a square foot of an article passed through the machine. Secured on the outer end of the hollow shaft 93 by a screw 107 is a hand 108 which is adapted to be moved over the 105 dial by the gearing described. Fixedly secured on the end of the hollow shaft 82, opposite to that at which the gear 90 is mounted, is a gear 109 (Fig. 4) which is in mesh with a larger gear 110. The gear 110 is 110 secured on a shaft 111 (Figs. 5 and 6) which is rotatably mounted in brackets 112 secured on the back plate of the machine. Surrounding the shaft 111 is a coiled spring 113 (Fig. 4) one end of which is secured 115 by a screw 114 to the side of the gear wheel 110, and the other end to the bracket 112 remote from said gear wheel. The rod 85 (Figs. 4, 6 and 7) projects beyond the hub of the gear 109 and is provided in its outer 120 end with a recess portion 115 which receives the upper bifurcated end of a lever 116 which is pivotally mounted at 117 on a post 118 (Fig. 6) projecting from the back plate of the machine. The lower end of 125 the lever 116 is in the path of a cam portion 119 of a push pin 120 the inner end of which is slidably mounted on a pin 121 projecting from the back plate of the machine and which is surrounded by a coiled 130

spring 122 which normally presses the push pin outwardly. By pushing in the pin 120 against the resistance of the spring 122 the lever 116 will be rocked by engagement with 5 the cam surface 119 to draw the rod 85 outward and thereby disengage the clutch members 81 and 89. This operation permits the automatic return of the dial hand to zero position through the action of the 10 spring 113 as will later be described. Secured on top of the push pin 120 is a spring clip 123 having an arm 124 which engages with a ratchet wheel 125. This ratchet wheel is fast on a shaft 126 which operates 15 a counting mechanism, indicated generally by the numeral 127, mounted on a bracket 128. This mechanism is of the usual construction and of itself constitutes no part of the invention and need not be particularly 20 described, as its operation is well known to those skilled in the art. The shaft 126 extends beyond the casing of the registering mechanism and on its outer end is provided with a bevel gear 129 which is in mesh 25 with a bevel gear 130 mounted on a shaft 131 which is rotatably supported in a bracket 132 secured on the end of the casing of the registering mechanism. The shaft 131 projects through the front casing member 11 of the machine and is provided with a turn button 133 by means of which the 30 counting mechanism may be reset to zero. This counting mechanism is operated from the ratchet wheel 125 by the arm 124 whenever the push pin 120 is pressed inward to 35 reset the dial hand after each hide has been measured, and is for registering the number of hides measured. The gear wheel 76 of the intermediate member 75 of the final 40 differential-gear unit is in mesh with a gear 134 (Fig. 4) which is fast on one end of a long shaft 135 which is supported in brackets 136. The opposite end of this shaft has secured thereon a gear 137 which is in mesh 45 with a similar gear 138 which is fast on one end of a shaft 139 which operates a totalizing or registering mechanism, indicated generally by the numeral 140, mounted on a bracket 141 (Fig. 7), and which, being of 50 any well known construction need not be specifically described. The shaft 139 extends through the casing of this registering mechanism and on its opposite end is provided with a bevel gear 142 which is in 55 mesh with a bevel gear 143 which is fast on the end of a shaft 144 which is supported on a bracket 145 secured on the end of the casing of the totalizing mechanism. The shaft 144 projects through the front casing member 60 and is provided with a turn button 145 by means of which the totalizing mechanism may be returned to zero when desired.

The measuring wheels 38 are, in the present embodiment of my invention, four and

one-half inches in circumference, and assuming that the distance between centers of said wheels is one inch, if all of the measuring wheels are given one complete revolution it is apparent that this is equivalent to moving a sheet of material, thirty-two inches in width, four and one-half inches lineally, so that one hundred and forty-four square inches, or one square foot, of such material would be moved forward. 70 By aggregating the movements of these measuring wheels in the manner set forth, as the intermediate member of any differential unit will make one revolution for each complete revolution of the two outer members of the unit, it follows that the final differential unit 75 will be given one complete revolution for each complete revolution of all of the measuring wheels 38; and by connecting the intermediate gear 76 of this 75 final aggregating member with the registering mechanism 140 by suitable gearing, such registering mechanism will be caused to indicate one square foot for every revolution of said final aggregating member, or fractional part of a square foot for a less degree of movement. This follows from the fact that as all of the measuring wheels rotate, all of the differential-gear units, including the final one will rotate at the same rate of 80 speed; and if any one or more of the measuring wheels ceases to rotate, its portion of the total movement is automatically deducted from the movement of the final differential unit. 95

As the gear 76 of the final unit is revolved it not only actuates the registering mechanism 140, as above described, but through the medium of the gears 78 and 80, clutch members 81 and 89, bevel gears 90 and 92 100 and hollow shaft 93 rotates the hand 108 over the face of the dial 106. Furthermore as the clutch member 89 is revolved it causes the revolution of the gears 109 and 110 by rotating the hollow shaft 82, through the 105 pin and slot mechanism described. Each rotation of the gear 110 causes the coil spring 113 to be wound up. When the hide has passed through the machine it is, of course, necessary to return the dial hand 108 to 110 zero. This is effected by pushing in the push pin 120 which throws the upper end of the lever 116 outward, thereby drawing the rod 85 outward and by the engagement of the pin 86 with the clutch member 81 operates to move said clutch member out of engagement with the clutch member 89, so that the latter is free to be rotated by the revolution of the shaft 111 caused by the 115 unwinding of the coil spring 113 through the medium of the gears 110, 109 and hollow shaft 82. In this movement the bevel gears 90 and 92 will have their movements reversed and by rotating the shaft 93 in the 120 opposite direction to that first described will 125 130

return the hand 108 backward. In order to stop the hand at zero I provide the following mechanism:

The numeral 146 (Fig. 4) indicates a bracket secured on the rear wall 8 on which is pivotally mounted at 147 a double dog, one arm 148 of which is adapted to be engaged by a pin 149 on the gear wheel 101 and the other arm 150 of which is adapted 10 to engage a shoulder 151 on the cam plate 95. The movement of the double dog occasioned by the contact of the pin 149 of the arm 148 is made against the resistance of a spring clip 152 secured at one end on the bracket 15 146 and having its other end engaging over the upper side of the arm 148. As the hollow shaft 93 rotates, the cam plate 95 and the pinion 96 are rotated with it, and the latter causes the rotation of the gears 99, 20 100 and 101. The latter, as stated carries the pin 149, and the parts are so adjusted that this pin will engage the arm 148 and turn the arm 150 upward to engage the shoulder 151 of the cam plate 95, and thereby stop 25 the revolution of the parts described, when the hand 108 arrives at the zero position. As heretofore indicated, when the push pin 120 is pushed inward to permit the dial hand to return to zero, the arm 124 carried by the 30 push pin will move the ratchet wheel 125 the proper distance to cause the counting mechanism 127 to indicate that a hide has passed through the machine.

From the foregoing description of the operation of the machine it will be seen that 35 the only limit to the speed, or capacity, thereof is the dexterity of the operator in supplying hides thereto, the resetting of the dial hand consuming only a moment of time; 40 and that the measuring wheels and all of the aggregating units may be moved continuously in the same direction without any resetting or adjustment of any kind whatever being required. It will furthermore be seen 45 that, assuming the accuracy of the gears, the movement of the measuring wheels is aggregated and translated accurately into movement indicating measurement, such as that of the dial hand, or the disks of the registering device.

So far as I am aware the means herein described for aggregating the movement of a series of measuring wheels to integrate surface area is broadly new; and I wish to be 50 understood as claiming the same generically and without limitation to specific details of construction or to the precise number and arrangement of the parts described.

Should the motor 21 be employed it will 55 be understood that the feed roller 17 will be constantly revolved; and that if the machine is manually operated, as by the crank handle 20, the feed roller will then be revolved only so long as the crank handle is 60 turned. With either manner of rotating the

feed roller, the feed wheels 35 rest by gravity, first upon the feed roller 17 and then upon the material as it is passed between the feed roller and feed wheels, and operate by their weight to produce the necessary 70 grip of the feed roller 17 on the material to cause the latter to be pulled through the machine in contact with the measuring wheels 38. The feed roller 17, of course, is the only power-driven part of the machine, all 75 of the measuring wheels and the differential-gear units being caused to rotate by contact of the moving material with the measuring wheels.

I claim:—

1. In a machine of the class described, in combination with a series of yieldably-mounted measuring wheels adapted to be actuated by the material to be measured, registering mechanism, and a series of rotatable 85 aggregating members operatively engaged with said measuring wheels and said registering mechanism, respectively, and capable of rotating continuously indefinitely in the same direction when the machine is used. 90

2. In a machine of the class described, in combination with a series of yieldably-mounted measuring wheels adapted to be actuated by the material to be measured, registering mechanism, and a series of rotatable 95 aggregating members in geared relation with each other, and with said measuring wheels and said registering mechanism, respectively.

3. In a machine of the class described, in combination with a series of yieldably-mounted measuring wheels adapted to be actuated by the material to be measured, a series of connected rotatable aggregating members co-ordinated with said measuring 100 wheels and continued therefrom in diminishing numbers to unity, and a registering device in co-operative engagement with the unitary aggregating member.

4. In a machine of the class described, in combination with a series of yieldably-mounted measuring wheels adapted to be actuated by the material to be measured, registering mechanism, and a series of differential-gear aggregating units operatively 110 engaged with said wheels and said registering mechanism, respectively.

5. In a machine of the class described, in combination with a series of yieldably-mounted measuring wheels adapted to be 115 actuated by the material to be measured, registering mechanism, and a plurality of series of connected differential-gear aggregating units successively diminishing in number to unity, the series having the 120 greater number of units being operatively connected with said measuring wheels, and the unitary aggregating device being operatively connected with said registering mechanism. 130

6. In a machine of the class described in combination with a series of yieldably-mounted measuring wheels adapted to be actuated by the material to be measured and each of which is provided with a gear, a plurality of series of differential-gear units, successive series of said units diminishing in number by one-half to unity, adjacent pairs of said measuring wheels having their gears in mesh with the outer gear members of successive members of the first series of aggregating units, the intermediate members of adjacent pairs of said first series of aggregating units having their gear members in mesh with the outer members of a second series of said differential-gear units, and successive series of said units being similarly associated up to the final aggregating unit, registering mechanism having an actuating gear operatively connected with the intermediate gear member of said unitary aggregating member, and a continuously rotatable feed device cooperating with said measuring wheels.
- 10 7. In a machine of the class described in combination with a series of measuring wheels adapted to be actuated by the material to be measured, registering mechanism, a series of rotatable aggregating members operatively engaged with said measuring wheels and said registering mechanism, respectively, and means for resetting said registering mechanism to zero independently of the movement of said aggregating members.
- 15 8. In a machine of the class described, in combination with a continuously rotatable feed roller, a series of independent, yieldably-mounted measuring wheels supported in proximity to, but out of contact with said feed roller and adapted to be actuated by sheet material passed between them and said feed roller, registering mechanism, and a series of rotatable aggregating members operatively engaged with said measuring
- 20 9. In a machine of the class described, in combination with a continuously rotatable feed roller, a series of pivoted supports located adjacent to said feed roller, a measuring wheel mounted in each of said supports and held thereby in proximity to, but out of engagement with, said feed roller, the series of measuring wheels being adapted to be actuated independently of each other by sheet material passed between them and said feed roller, registering mechanism, and a series of rotatable aggregating members operatively engaged with said measuring wheels and said registering mechanism, respectively, and capable of rotating continuously indefinitely in the same direction when the machine is used.
- 25 10. In a machine of the class described, in combination with a continuously rotatable feed roller, a series of yieldably-mounted feed wheels resting by gravity on said feed roller, a series of yieldably-mounted measuring wheels located with their surfaces in proximity to, but out of contact with, said feed roller, and adapted to be actuated by sheet material passed between them and said feed roller, registering mechanism, and a series of rotatable aggregating members operatively engaged with said measuring wheels and said registering mechanism, respectively, and capable of rotating continuously indefinitely in the same direction when the machine is used.
- 30 11. In a machine of the class described in combination with a series of yieldably-mounted measuring wheels adapted to be actuated by the material to be measured, registering mechanism and means for connecting the measuring wheels with the registering mechanism to drive the same, said means consisting of a plurality of wheels capable of rotating continuously and indefinitely in the same direction during the use of the machine.
- 35 In testimony whereof, I have hereunto set my hand.

WALTER E. HOSCH.
